UNITED STATES PATENT OFFICE.

JOSEPH LOCKE, OF DICKSON, TENNESSEE.

HAMMOCK-SUPPORT.

No. 893,083.

Specification of Letters Patent.

Patented July 14, 1908.

Application filed September 23, 1907. Serial No. 394,208.

To all whom it may concern:

Be it known that I, JOSEPH LOCKE, a citizen of the United States, residing at Dickson, in the county of Dickson and State of Tennessee, have invented a new and useful Hammock-Support, of which the following is a specification.

This invention has reference to improvements in hammock supports, and its object is to provide a portable support for hammocks wherein the parts are effectually braced in the several positions of adjustment, and the whole structure may be folded up into small compass for storage or shipment.

The invention comprises essentially a main connecting bar or sill, the length of which may be adjusted at will, and at each end this sill is received in suitable sockets carried by laterally extended feet or supports. There are also provided hammock carrying uprights removably connected at their lower ends to the feet or supports on opposite sides of the sill or connecting bar, these uprights being formed of two strips with their lower ends spread apart and their upper ends connected, or, if need be, and especially when made of metal, these uprights may be constructed of one piece suitably shaped for the purpose. Pivotaly connected to each upright is a brace rod, while the connecting bar or sill is provided with an appropriate number of spaced sockets for receiving the free ends of the brace rods, so that the inclination of the uprights may be fixed at will to provide means whereby the relative height of the head and foot portions of the hammock may be adjusted to suit the user.

The invention will be best understood by reference to the following detailed description, taken in connection with the accompanying drawings forming part of this specification, in which,—

Figure 1 is a perspective view of the hammock support, with a hammock indicated in broken lines; and Fig. 2 is a detail view of a caster support.

Referring to the drawings, there is shown a longitudinal sill or bar 1 composed of two pieces 2—3 connected together by yokes or straps 4, so that these pieces may be adjusted longitudinally one on the other to extend the bar 1 to its total length or to reduce its length as desired. The straps 4 may be so related to the two pieces 2—3 that any longitudinal movement of these pieces, especially any tendency to telescope, will be re-

sisted by the cramping action of the yokes or straps. Furthermore, the yokes may be secured to one piece, say the piece 2, and be without connection to the part 3 except by the cramping action due to the tendency of the bar sections to telescope.

There are provided two laterally extending feet or supports 5—5 of sufficient spread to resist any tendency to upset the structure by lateral strains. The upper face of each foot or support 5 is flattened and at the center of the flattened portion there is secured a socket structure 6 shaped to receive the free end of one or the other of the parts 2 and 3. These sockets 6 may be so constructed as to receive these ends in a manner to prevent their passing through the same, either by making them slightly tapered with a corresponding taper on the ends of the bar sections 2 and 3, or by the use of a through pin, or any other means whereby these ends of the bar or sill are held to the supports 5 but are still removable therefrom. On each side of the socket 6 on each support 5 there is secured a plate 7 having an upwardly extending ear 8 carrying a laterally projecting pin 9. These pins receive eyes formed in the ends of straps 10 on the lower extremities of the two legs 11 of an upright 12. In this particular structure the upright 12 is shown formed in two parts brought together at the upper ends and there secured by a bolt 13 and if need be, by other means, and the legs 11 diverge toward the lower ends where they carry the straps 10. About midway of the length of the legs 11 there is another through bolt 14 upon which is mounted a sleeve 15 having about midway of its length a laterally extending ear 16 to which is secured a rod 17 by a screw or bolt 18, while the other end of this rod 17 is bent as shown at 19 so as to engage in any one of a series of holes or sockets 20 formed in the top of the respective section 2 or 3 of the bar or sill 1. Near the top of each upright 12 there is an eye 21 to receive the ordinary end hooks 22 of a hammock 23.

Now, let it be assumed that the structure is in the disassembled state and a user desires to so assemble it as to receive a hammock. The bar 1 is extended until it is of the proper length and the ends are then seated in the sockets 6. The uprights 12 are then secured to the supports 5 by slightly spreading the lower ends of the legs so that the eyes in the straps or plates 10 will snap

over the pins 9 on the brackets 7, and then the rods 17 are so moved that their ends 18 will engage in any desired one of the sockets or holes 20 in the bar sections 2 and 3. If 5 the inclination of the uprights 12 is not suitable then one or the other of the rods 17, as the case may be, is lifted so that its end 18 is free from the perforation 20, this being possible because the sleeve 15 is movable about 10 the bolt 14 as a horizontal pivot, and the end 18 is then reinserted in a suitable one of the holes 20. By this means the inclination of the uprights 12 may be alike, or they may be different, according to the desires of the 15 user. Now, when the hammock is hung in the eyes 21 and the user is seated or reclines in said hammock the weight thus applied to the hammock tends to draw the ends of the uprights 12 toward each other. This, however, 20 is resisted by the brace rods 17 which only tend to seat themselves more firmly in the sockets or perforations 20 because of the strain brought upon the uprights 12. At the same time any tendency of the bar sections 25 2 and 3 to telescope one on the other is resisted by the cramping action of the yokes or straps 4.

Any side strain of the hammock which would tend to upset the structure is resisted 30 by the wide spread of the supports 5, and all side strain thus brought to bear upon the uprights 12 is resisted by the spread of the legs 11 at their lower ends, being connected at divergent points on opposite sides of the sill 1 35 to the supports 5. The supports 5 may be mounted upon casters 24, the stems 25 of which are supported by springs 26, so that

the whole structure is elastically upheld and at the same time these casters permit the hammock support as a whole to be moved 40 from place to place without the necessity of dismantling it. The springs in the casters are of sufficient strength to render the whole support elastic and thereby add to the comfort of the user. 45

The structure may be made of wood and metal, or entirely of metal when so desired.

I claim:—

A hammock support comprising a bar or sill composed of two members telescoping 50 one on the other, each member being provided with a series of perforations or sockets, laterally extending feet or supports each having a socket for the reception of the corresponding end of the sill, hammock supporting uprights, one for each foot or support, each of said uprights having divergent members pivotally connected at their lower ends to the corresponding foot or support, a connecting bolt or rod for the said members of 60 the upright, a spacing sleeve thereon having a projecting ear, and a brace rod connected to said ear at one end and having its other end adapted to any one of the corresponding series of perforations or sockets in the sill, the 65 bolt extending through the sleeve constituting a pivot support for the brace rod.

In testimony that I claim the foregoing as my own, I have hereto affixed my signature in the presence of two witnesses.

JOSEPH LOCKE.
